GAME

Cecil Moulton McGennis, Calgary, Alberta,
Canada

Application August 11, 1937, Serial No. 158,603

3 Claims. (Cl. 273—134)

This invention relates to games.

It is an object of the present invention to provide a game which will produce conditions during the course of play as true to life as possible, 5 wherein each player may encounter various misfortunes or successes and as in life acquire additional wealth or severe losses in speculation.

A further object of the invention is to provide a game which is simple to play and in which 10 the values obtained at any given time may be readily ascertained without complication.

A further object of the invention is to provide a game wherein stock market values are involved and in which these values fluctuate from time to 15 time in the course of play and may readily be ascertained on the market board or boards.

A further object of the invention is to provide an interesting game which may be played by a number of players or may, if desired, be played 20 by a single player.

With these and other objects in view the invention consists essentially in a game having a board and markers for each player to be moved on the board, the board having a general track 25 divided into suitable spaces bearing indicia over which the markers are caused to be moved in one direction, and upon which the markers are caused to rest, the board having associated therewith a plurality of sets of cards selected by the 30 indicia on the spaces.

Included with said cards are sets of cards in turn associated with market boards having price lists and a sliding scale for determining the market values, stock certificates being employed 35 which are valued according to the fluctuating values on the market boards. In addition to stock certificates, play money is included whereby each player may pay losses or collect gains occasioned by fluctuation of the markets or race 40 track bets, while dice are also included for determining the extent of travel of the marker of each player during the course of play and thus for determining the actions of each player, as fully described in the following specification and 45 illustrated in the accompanying drawings.

In the drawings:

Figure 1 illustrates a general plan view of the game board employed in accordance with the present invention.

Figure 2 is a plan view of the stock market 5 board illustrating the sliding device for determining the values of the stock.

Figure 3 is a plan view of the sliding device for the stock market board.

Figure 4 is a section taken on the line 4—4 10 of Figure 2.

Figure 5 is a plan view of the grain market board.

Figure 6 is a plan view of the sliding device employed on the grain market board to determine the values from time to time.

Figure 7 is a plan view of a stock certificate employed with the game.

Figure 8 is a plan view of the reverse side of the stock certificate illustrating the loan value 20 of the certificate and the amount for redemption of the loan.

Figures 9 and 10 are plan views of a wheat certificate and its reverse side respectively.

Figure 11 is a plan view of one of the controlling cards from the stock market employed on the game board.

Figure 12 is a plan view of a general welfare card employed on the game board.

Figure 13 is a plan view of a race track card 30 employed on the game board, and

Figure 14 is a plan view of the play money which may be employed with the game.

Referring to the drawings, 10 indicates the 35 game board which is preferably square and is provided around its margin with a track 11 marked off into a series of spaces which are labelled in consecutive order from 1 to 50. The board employs a plurality of markers of any suitable shape or design, one marker being illustrated by the numeral 12 appearing on the space labelled as 1, other markers also indicated by the numeral 12 being shown as conveniently placed in the centre of the board ready for use. A 40 45

marker is used by each player, each of which may be placed on the starting space 14. Dice are employed to control the movement of the markers around the track 11 and the dice may be used to determine the first one to start, for instance, the player throwing the highest number might be given this privilege. The markers are moved around the track a number of spaces corresponding to the number turning up at each throw of the dice, and the spaces are provided with directions which must be followed by the player when his marker is moved onto any one of them.

The directions in general concern stock market and grain market speculations occurring in spaces indicated by the numeral 13, race track ventures, as will be later referred to, and general instructions noted on the board as general welfare and indicated by the numeral 15, whereby all players in the game are affected. Certain of the spaces such as the starting space 14 and spaces 16, 17, 18, 19 and 20 include directions whereby the player must move the marker as directed or cannot move the marker, but must act otherwise according to directions. Other spaces, such for instance as indicated by the numeral 21, contain other instructions which must be followed according to direction.

Associated with the spaces 14, 15, 17, 18 and 20 are controlling cards to determine the transactions of each player when his marker is moved to any one of these spaces. There are four sets of cards, set A corresponding to certain of the spaces 13, set B corresponding to the remainder of the spaces 13, set C corresponding to the spaces 15 and set D corresponding to the spaces 14, 17, 18 and 20. Thus, a player moving onto a space 13 must pick up a card from a set A or set B, depending as to whether the space concerns the stock market or grain market, and act in accordance with the instructions given on said card. For instance, in Fig. 11, a card from set A is shown with instructions to buy 20 shares of Automotive Corporation from the stock market. Similarly if the player's marker is moved to one of the spaces 15 or one of the spaces 14, 17, 18 or 20, he must take a card from set C or set D respectively. As shown in Fig. 12, the cards corresponding to the spaces 15 and having to do with general welfare, affect all players. As an illustration, the stock market drops five points so that the stock held by all players is depreciated. In the case of set D having to do with race track transactions, a card is illustrated in Fig. 13 whereby the player wins on a bet placed at the race track.

Associated with the sets of cards A, B and C are market boards such as a stock market board 22, see Fig. 2, and the grain market board 23, see Fig. 5. In the case of the stock market board 60 there are employed several columns of figures 24, certain of which are designed to represent a given stock, the columns being divided off into a series of equal spaces with gradually increasing and decreasing values occurring in said spaces above 65 and below respectively the center set of spaces 25 which represent par value of the stock. Over the board is placed a sliding member 26 which is preferably of tubular construction so that it can slide 70 over the board 22, the center of the member 26 being slotted as at 27 so that one space of figures across all columns may be disclosed. The sliding member 26 is divided off into columns 28 corresponding with the columns of figures 24 on the board, and in the columns 28 the names of the

stock are inserted to designate what stocks are represented by the various columns on the board.

The two outside columns on the board carry figures to indicate fluctuation on the board and the outer columns on the sliding member 28 are marked to correspond with market fluctuations. It will be apparent, therefore, that if a card is taken from the set C and the card is that shown in Fig. 12 wherein the stock market drops five points, the sliding member 26 is moved downwardly below the par value to the numerals 5 occurring in either of the outside columns 24 of the board, whereupon an intermediate column gives the current value of the stock concerned. The same course is followed when the stock market rises, the sliding member 28 being moved up on the board above the center point or above par value the given number of points indicated on the card from set C and indicated on the board in either outside column.

The grain market 23 is laid out on exactly the same plan, including columns of figures 24, sliding member 26 as shown in Fig. 6, which is divided off into columns 28 corresponding with market fluctuations and the various grains which may be bought. Thus the buying and selling on the grain market or stock market is controlled according to the card drawn from sets A or B and these cards directly affect the player drawing them and may affect other players at the same time. Certain cards in these series may control the loans held by the player, as will be noted from the lists of cards appearing hereinafter.

Certificates for stocks and for grain buying are provided as indicated in Figs. 7 to 10, each certificate indicating the amount of the share or the number of bushels of grain it represents. On the reverse side of the certificate the loan value thereof is given to indicate what amount of money may be obtained on them from the bank, whereas the certificate also discloses the amount payable to the bank for the redemption of certificates. The certificates are held by the player as they are bought and are placed on the table adjacent to the game board and if loans have been obtained on them they are turned face downwards so as to indicate that a loan has been obtained on them and the loan value. Thus at a glance a player's obligation can be determined, whereas the value of the certificate may be readily noted from the current prices on the stock market and grain market boards.

Suitable play money is provided so that all monetary transactions may be carried out during the course of the game. A suitable form of play money is illustrated in Fig. 14.

In the preferred arrangement for the game the following certificates and cards are employed.

Stock certificates

There are 10 ten share certificates for each of the six pseudo companies, as follows:

Automotive Corporation.....	Loan value \$500—to redeem, pay \$550.
Continental Railway.....	Loan value \$400—to redeem, pay \$440.
General Utilities Ltd.....	Loan value \$400—to redeem, pay \$440.
National Canneries Ltd.....	Loan value \$300—to redeem, pay \$330.
Peoples Oil Corporation.....	Loan value \$300—to redeem, pay \$330.
Standard Steel Company.....	Loan value \$300—to redeem, pay \$330.

Grain bill of sale

There are 11 grain certificates listed for one thousand bushels each, giving the face value on the certificate and as above indicated the loan value on the reverse side and the amount to be

repaid to the bank when they are redeemed. These are as follows:

Barley	Loan value \$300—to redeem, pay \$330.
Flax	Loan value \$600—to redeem, pay \$660.
Oats	Loan value \$300—to redeem, pay \$320.
Rye	Loan value \$400—to redeem, pay \$440.
Wheat	Loan value \$500—to redeem, pay \$550.

Stock market cards

10 These consist of a set of 58 cards printed on one side only, as follows:

Number of cards	Printing
15	
1	Player has option of buying 10 shares Automotive Corporation.
3	Buy 10 shares Automotive Corporation.
1	Player has option of buying 20 shares Automotive Corporation.
20	Buy 20 shares Automotive Corporation.
1	Player has option of buying 10 shares Continental Railway.
3	Buy 10 shares Continental Railway.
1	Player has option of buying 20 shares Continental Railway.
2	Buy 20 shares Continental Railway.
1	Player has option of buying 10 shares General Utilities Ltd.
25	Buy 10 shares General Utilities Ltd.
1	Player has option of buying 20 shares General Utilities Ltd.
2	Buy 20 shares General Utilities Ltd.
1	Player has option of buying 10 shares National Canneries Ltd.
30	Buy 10 shares National Canneries Ltd.
1	Player has option of buying 20 shares National Canneries Ltd.
2	Buy 20 shares National Canneries Ltd.
1	Player has option of buying 10 shares Peoples Oil Corporation.
3	Buy 10 shares Peoples Oil Corporation.
1	Player has option of buying 20 shares Peoples Oil Corporation.
35	Buy 20 shares Peoples Oil Corporation.
1	Player has option of buying 10 shares Standard Steel Company.
3	Buy 10 shares Standard Steel Company.
1	Player has option of buying 20 shares Standard Steel Company.
40	Buy 20 shares Standard Steel Company.
8	Sell your shares.
4	Player has option of selling all shares held.
2	All players sell your shares.
1	Bank calls your loans. Sell shares and grain if necessary.
45	Bank calls all loans. Players must sell shares and grain if necessary.

Grain market cards

50 These cards, similarly to the stock market cards, are printed only on one side and consist of a set of 59 cards as follows:

Number of cards	Printing
55	
1	Player has option of buying 1000 bushels barley.
4	Buy 1000 bushels barley.
1	Player has option of buying 2000 bushels barley.
2	Buy 2000 bushels barley.
60	Player has option of buying 1000 bushels flax.
3	Buy 1000 bushels flax.
8	Player has option of buying 1000 bushels oats.
1	Buy 1000 bushels oats.
4	Player has option of buying 2000 bushels oats.
1	Buy 2000 bushels oats.
2	Player has option of buying 1000 bushels rye.
1	Buy 1000 bushels rye.
4	Player has option of buying 2000 bushels rye.
1	Buy 2000 bushels rye.
2	Player has option of buying 1000 bushels wheat.
1	Buy 1000 bushels wheat.
4	Player has option of buying 2000 bushels wheat.
1	Buy 2000 bushels wheat.
2	Sell your grain.
8	Player has option of selling all grain held.
1	All players sell grain.
70	Bank calls your loans. Sell shares and grain if necessary.
1	Bank calls all loans. Players must sell shares and grain if necessary.

General welfare cards

These include 70 cards printed on one side such as shown in Figure 12 and are as follows:

Number of cards	Printing	5
1	Stock market rises 1 point.	
1	Stock market rises 2 points.	10
1	Stock market rises 3 points.	
1	Stock market rises 4 points.	
1	Stock market rises 5 points.	
1	Stock market rises 6 points.	
1	Stock market rises 7 points.	
1	Stock market rises 8 points.	
1	Stock market rises 9 points.	
1	Stock market rises 10 points.	15
1	Stock market drops 1 point.	
1	Stock market drops 2 points.	
1	Stock market drops 3 points.	
1	Stock market drops 4 points.	
1	Stock market drops 5 points.	
1	Stock market drops 6 points.	
1	Stock market drops 7 points.	20
1	Stock market drops 8 points.	
1	Stock market drops 9 points.	
1	Stock market drops 10 points.	
1	Grain market rises 1 point.	
1	Grain market rises 2 points.	
1	Grain market rises 3 points.	
1	Grain market rises 4 points.	25
1	Grain market rises 5 points.	
1	Grain market rises 6 points.	
1	Grain market rises 7 points.	
1	Grain market rises 8 points.	
1	Grain market rises 9 points.	
1	Grain market rises 10 points.	
1	Grain market drops 1 point.	
1	Grain market drops 2 points.	
1	Grain market drops 3 points.	
1	Grain market drops 4 points.	
1	Grain market drops 5 points.	
1	Grain market drops 6 points.	
1	Grain market drops 7 points.	
1	Grain market drops 8 points.	
1	Grain market drops 9 points.	30
1	Grain market drops 10 points.	
7	Race track card—do not move marker, but player must place a bet at race track.	35
3	Race track card—do not move marker, but player has option of placing a bet at race track.	
1	All players sell your shares.	
5	All players sell your grain.	
3	Bank calls your loans.	40
1	Bank calls all loans.	
1	All players collect dividend of \$1 per share on all shares held.	
1	All players collect dividend of \$2 per share on all shares held.	
1	All players pay \$10 storage charges on every 1000 bushels of grain held.	
1	All players pay \$20 storage charges on every 1000 bushels of grain held.	45
1	Move forward 2 numbers.	
2	Move forward 5 numbers.	
2	Move backward 4 numbers.	
1	Move backward 5 numbers.	

Race track cards

These may consist of a set of 50 cards such as shown in Figure 13 and are as follows:

Number of cards	Printing	55
32	Your horse loses.	
4	Nonstarter. Collect refund.	
7	Your horse wins. Collect 2 to 1.	60
3	Your horse wins. Collect 3 to 1.	
1	Your horse wins. Collect 4 to 1.	
1	Your horse wins. Collect 5 to 1.	
1	Your horse wins. Collect 6 to 1.	
1	Your horse wins. Collect 8 to 1.	

The various cards above referred to and the corresponding spaces on the board are coloured so that the same colour will apply to stock market cards and the stock market spaces, as well as to the stock market certificates. Similarly, the general welfare spaces and general welfare cards are coloured to correspond in a colour different to the other cards and spaces. In this way each set of cards and corresponding set of spaces are 70 75

distinctly coloured so that they can be distinguished at a glance.

Play money

5 The play money is of similar design throughout but all the denominations are of a different colour and the amounts may be as follows:

50 X 10	500
50 X 20	1,000
10 50 X 50	2,500
50 X 100	5,000
50 X 500	25,000
35 X 1000	35,000
 15 Total	 69,000

15

The game may be played by any number of players and even as solitaire, as previously indicated. When played by two to six players, for instance, each player receives \$4,000 of play

20 money. If more than six are playing, only \$3,000 of play money is allotted to each person, the bank, race track, stock market and grain market holding the balance. Each player may receive one ten

25 dollar bill, two twenty dollar bills, three fifty dollar bills, three one hundred dollar bills, three five hundred dollar bills and two one thousand dollar bills. When two to six are playing and when more than six are playing, the same amounts are given with the exception that only one one

30 thousand dollar bill is allotted each person. At the start of each game the 58 stock market cards are shuffled and placed on the board at A. Similarly, the 59 grain market cards, the 70 general welfare cards and 50 race track cards are shuffled

35 individually and placed on the board at B, C and D respectively. The stock market and grain market fluctuating boards are set at par and the markers may be placed on space No. 1, indicated as the start. Following this, the dice, preferably

40 two in number, are thrown by the players in order of their turn, after the initial starter is selected, the markers being moved along the number of spaces indicated by the throw of the dice, whereupon the player follows the instructions

45 given on the spaces and selects one of the sets of cards, as the case may be and buys or sells stock or grain, places a bet at the race track, or causes the welfare of all concerned to be changed one way or another, according to instructions received on a general welfare card that might be drawn.

50 In this way the fortunes of each and all players are varied one way and another and the stock market and grain market boards are caused to fluctuate, the buying and selling transactions in these markets being controlled by the current price. After each card is drawn the card is placed at the bottom of the set and the play continues.

55 In stock market and grain market transactions, the maximum point either the stock market or grain market can reach is 25 above or below par. Should the market be, say, 20 above or below par and a general welfare card be turned up of 6 or more points, which would raise or lower the market beyond the maximum, no change is made in the market fluctuating board and the card is placed approximately in the middle of the general welfare deck and the player draws another card.

60 Should a player hold shares or grain and turn up a stock market or grain market card instructing to buy shares or grain which cost more than the play money which the player holds, he or she obtains a loan from the bank for the amount

stated on the reverse side of the stock or grain certificates. All certificates pledged to the bank for a loan must be turned over to show that the certificate is pledged as security for a loan.

65 If a player turns up a stock market or grain market card which calls for the purchase of shares or grain and the player has not sufficient funds to pay for the purchase, player borrows from the bank the amount specified on each certificate owned as well as the loan value as indicated on the certificates being bought (providing the latter loan is required to complete the payment of the purchase), but should the total loan value thus available plus cash on hand not be sufficient to pay for the purchased certificate(s), then the sale is obviously cancelled. The player's marker remains where it was placed, but the next player plays and the game goes on in the same manner as before. The player who could not complete his or her purchase, being in 20 the same position as in real life. If the market should rise this player would not be able to take advantage of the profit and the reverse should the market drop.

25 When a loan is made to a player the certificate(s) are pledged to the bank and is payable at call by the bank. The certificates, while retained by the player for convenience, must be turned over so that the loan and pledged side is uppermost to show that it is pledged to the 30 bank, and the loan is repaid, the amount payable is the amount of the loan, plus 10% interest (the rate set for call money).

35 When bank calls a loan or loans or all loans, the player or players affected must pay their loans, first from cash holdings and if not sufficient sell (first) shares in alphabetical order until sufficient funds are realized. Grain holdings also in alphabetical order, being the last sold. If market is below par and player cannot meet loan 40 the shortage is noted and the game is at once finished and all players sell their holdings and the winner is determined.

45 Should a player's marker rest on a storage charge or a general welfare storage charge card be turned up and any player has not sufficient funds on hand, he or she must obtain a loan from the bank against shares or grain holdings. If all certificates held are already pledged for loans, the player must sell shares, etc., in alphabetical order, pay off the respective loans and thus obtain the necessary funds to pay the storage charges. If sufficient funds cannot be raised by this procedure, the game is finished as the player is bankrupt. The shortage is noted and all players sell their holdings and the winner is determined.

50 Should the bank have all of its funds out on loan and a player require a loan to purchase stock or grain, the loan is declined and the player cannot complete the purchase. This should happen very rarely as the combined bank, stock and grain market brokers, etc. should always have funds on hand, unless all the players have won large amounts during the course of their play.

55 Should the bank be short of funds to pay out a dividend to a player, it must call all loans. If on rare occasions the bank is without funds with 70 which to pay a dividend and the bank has no money on loan to collect, the game is finished and players count the value of their holdings as cash and the winner is determined.

75 The length of time the game is to be played

should be determined at the start of the game and finished promptly at that set time unless, as previously explained, a player or the bank, etc., should become bankrupt.

5 It will be apparent, of course, that the number of cards, certificates, shares and the amount of money and its denominations may be varied. Likewise, the playing board might be differently arranged while the sliding member on the stock 10 and grain boards might be of different character. The foregoing preferred arrangement is illustrative of the general principle of the game which is designed to conditions during the course of play to be as true to life as possible.

15 Various modifications may be made in the invention without departing from the spirit thereof or the scope of the claims, and, therefore, the exact forms shown are to be taken as illustrative only and not in a limiting sense, and I desire that 20 only such limitations shall be placed thereon as are imposed by the prior art or are specifically set forth in the appended claims.

What I claim as my invention is:

1. In a game including a game board having 25 a track divided into a plurality of spaces bearing indicia over which markers are moved and on which markers are brought to rest and a set of cards corresponding to indicia on said spaces, each of said cards bearing instructions to be followed, certain of said instructions concerning market transactions, the combination with said game board and said cards of a market board 30 indicating market prices for different market conditions, shiftable means on said market board, said means being shifted on said market board in accordance with instructions on said cards to set the market price for all market transactions following a movement of said shiftable member.

2. In a game including a game board having 35 a track over which markers are moved and on which markers are brought to rest, said track being divided into spaces bearing indicia and including indicia concerning stock market, grain market and general instructions, a plurality of 40 sets of cards, each set corresponding with indicia on said track and bearing instructions to

be followed, one of said sets corresponding with indicia concerning the stock market, a second set corresponding with indicia concerning the grain market and a third set corresponding with indicia concerning general instructions, the combination 5 with said board and said sets of cards of stock market and grain market boards each operatively associated respectively with the first and second sets of cards and both operatively associated with the third set of cards, shiftable means 10 on said boards, said means being shifted in accordance with the instructions on the third set of cards, and setting the prices for the market transactions indicated by the first two sets of cards. 15

3. In a game including a game board having a track divided into a plurality of spaces bearing indicia over which markers are moved and on which markers are brought to rest, and a set of cards corresponding to the indicia on said 20 spaces, each of said cards bearing instructions to be followed, certain of said instructions concerning market transactions, the combination with said game board and said cards of a market board marked to provide columns, said columns 25 being divided into a plurality of corresponding spaces, said spaces in each column being in alignment with a series of corresponding spaces in the other columns, one series of aligned spaces being provided with symbols of a standard value, 30 the remaining spaces in each column, disposed above and below said series having standard values, being provided with symbols of gradually increasing and decreasing value respectively, a shiftable member disposed to slide on the market 35 board, said shiftable member having columns corresponding with the columns on the board, the columns on said shiftable member bearing indicia, said shiftable member being slidable to single out selected aligned spaces across the columns 40 and the symbols therein contained in accordance with instructions on said cards to set the market price for all market transactions which follow a movement of said member. 45

CECIL MOULTON McGENNIS.
